UNITED STATES PATENT OFFICE

2,648,149

VEHICLE ACTUATED GATE

Felix S. Sefcovic, Pueblo, Colo., assignor of fifty per cent to Bernstein Bros. Pipe & Machinery Company, Pueblo, Colo., a corporation of Colorado

Application September 13, 1949, Serial No. 115,501

3 Claims. (Cl. 39—37)

1

The present invention relates to new and useful improvements in gates and more particularly to a vehicle actuated swinging gate for farms and other purposes.

An important object of the invention is the provision of means for unlatching the gate and to cause the gate to swing open by the contact of a vehicle bumper with a latch releasing mechanism, so that the vehicle may continue through the gateway without the necessity of the driver alighting therefrom, and mounting the gate to automatically return to its closed position by gravity.

Another object of the invention is to provide a novel hinge structure for a gravity closing gate to swing the gate to its closed position without the aid of springs or other counterbalancing means.

A further object is to provide novel latch releasing means operated from both sides of the gate.

A still further object is to provide a gate operating mechanism of simple and practical construction, which is efficient and reliable in operation, strong and durable, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of the gate.
Figure 2 is a top plan view.

Figure 3 is an enlarged sectional view of the upper hinge structure taken on a line 3—3 of Figure 1.

Figure 4 is an enlarged sectional view of the lower hinge structure taken on a line 4—4 of Figure 1.

Figure 5 is an enlarged vertical sectional view taken on a line 5—5 of Figure 1 and showing the lever releasing mechanism for the latch.

Figure 6 is an enlarged horizontal sectional view taken on a line 6—6 of Figure 1 and showing the bumper contacting guards.

Figure 7 is an enlarged vertical sectional view of the latch taken on a line 7—7 of Figure 1.

Figures 8 and 9 are enlarged fragmentary sectional views taken respectively on the lines 8—8 and 9—9 of Figure 1, and

Figure 10 is a fragmentary view in elevation of the hinged end of the gate showing the angle of the gate when in open position.

2

Referring now to the drawings in detail, wherein for the purpose of illustration I have disclosed a preferred embodiment of my invention, the numeral 5 designates a tubular metal gate frame 5 provided with solid vertical bars 6 and a substantially centrally disposed tubular vertical bar 7. Horizontal rubber covered guards 8 extend from the central bar 7 to the edge of the gate frame to prevent hooking of a vehicle bumper guard with the gate upon contact therewith.

The inner end of the gate is hinged to a gate post 9 by an upper hinge structure designated generally at 10 and a lower hinge structure designated generally at 11.

Upper hinge structure 10 comprises a threaded rod 12 passing horizontally through post 9 and adjusted inwardly and outwardly therein by front and rear nuts 13 and 14. The front end of rod 12 is formed with a horizontal, triangular loop 15 having united arcuate front portions 16 curved eccentrically to each other to provide a seat 16a at the center of the front of the loop. A roller 17 is journaled on a pin 11a secured to frame 5 by a pair of brackets 18, the roller traveling in loop 15 to settle in seat 16a when the gate is closed.

Lower hinge structure 11 comprises a threaded rod 19 passing horizontally through post 9 and adjusted inwardly or outwardly by front and rear nuts 20 and 21, the front end of rod 19 having an upstanding pin 22 on which a ball bearing assembly 23 is journaled and having trunnions 24 rockably mounted in a yoke 25 at the rear end of a threaded rod 26 adjustably secured at the lower rear edge of gate frame 5 by nuts 27.

At the front or free end of gate frame 5 is a vertical latch bar 28 pivoted on the gate by a bracket 29 for inward and outward swinging movement of the upper end of the latch into and out of a notch 30 in the edge of a keeper plate 31 fixed to a gate post 32. The edge of the keeper plate is inclined from notch 30 toward the opposite ends of the plate to guide the latch into the notch and a roller 33 is journaled on the latch bar to reduce friction. A tension coil spring 34 is attached to the lower end of latch bar 28 to hold its upper end in an outwardly inclined position for engaging keeper 31 and the upper end of the latch bar above roller 33 is provided with an upper roller 35 which works in a guide 36 secured to gate 5 to prevent twisting of the latch.

A pair of cables 37 extend from latch bar 28 at opposite sides of the gate through guides 38 on central bar 7 and around pulleys 39 journaled 55 on a vertical support 40 also adjacent the center

of the gate, the cables extending outwardly from opposite sides of the gate for attaching to the upper ends of vertical levers 41.

Levers 41 are pivoted adjacent their upper ends on a pin 42 extending between support 40 and a second vertical support 43 parallel thereto and which also carry a plate 44 holding a pair of compression coil springs 45 in engagement with the inner lower edges of levers 41 to hold the lower ends of the levers outwardly and to hold the upper ends of the levers inwardly with a slight slack in cables 37.

Vertical guards 46 project outwardly from opposite sides of supports 40 and 43 and at each side of and beyond levers 41 to prevent injury thereto, the lower ends of the guards tapering inwardly to expose the lower ends of the levers to impact by a vehicle bumper approaching the gate from either side.

In the operation of the device, bar 28 normally holds the gate in its closed position under tension of spring 34 and as a vehicle approaches the gate and its front bumper strikes the lower end of lever 41, the upper end of the lever will swing outwardly pulling cable 37 to release latch bar 28 and the continued movement of the vehicle through the gate will push the gate open to permit passage of the vehicle.

Upper and lower hinge structures 10 and 11 are adjusted to position pivot pin 22 of lower hinge structure 11 inwardly of the vertical plane of the pivot of upper hinge structure 10, toward post 9. Accordingly, as the gate swings into its open position, as shown by dotted lines in Figure 3, roller 17 of upper pivot bracket 18 will travel along one curved side of loop 15, as shown in Figure 3 and since the line of incidence of upper and lower pivots, when the gate is open, is less than that when the gate is closed, as indicated at A and B in Figures 1 and 10, the front end of the gate will be raised when opened and thus the gate will return to its closed position by gravity.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a

preferred embodiment of the invention the same is susceptible to certain changes fully comprehended by the spirit of the invention as herein described and the scope of the appended claims.

Having described the invention, what is claimed as new is:

1. A vehicle actuated gate comprising means hinging one end of a gate to a gate post for automatic closing movement of the gate, a latch at the free end of the gate holding the gate in closed position, a vertical lever pivoted intermediate its ends at each side of the gate with the lower ends of the levers in the path of a vehicle approaching the gate from opposite directions for swinging the lower ends of said levers inwardly of the gate by impact of the vehicle to swing the outer ends of said levers outwardly of said gate, guards on said gate at opposite sides of said levers exposing the lower ends of said levers to impact by the vehicle and preventing impact of the vehicle with said levers above said lower ends, and means connecting the upper ends of said levers separately to said latch for releasing said latch by outward swinging of said upper ends.

2. A vehicle actuated gate according to claim 1 wherein said last named means comprises a pull cable extending between the upper end of each lever and said latch, and guides on said gate for said cables for causing outward movement of said upper ends to exert pull on said cables.

3. A vehicle actuated gate according to claim 1 wherein said last named means comprises a pull cable extending between the upper end of each lever and said latch, said levers upon outward movement of the upper ends thereof exerting pull on said cables.

FELIX S. SEFCOVIC.
